UNITED STATES PATENT OFFICE.

CHARLES A. JUENGST, OF CROTON FALLS, NEW YORK, ASSIGNOR TO AMERICAN ASSEMBLING MACHINE COMPANY, A CORPORATION OF DELAWARE.

VARIABLE-SPEED CONVEYER.

1,271,906.

Specification of Letters Patent.

Patented July 9, 1918.

Application filed October 18, 1916. Serial No. 126,294.

To all whom it may concern:

Be it known that I, CHARLES A. JUENGST, a citizen of the United States, and a resident of Croton Falls, in the county of West-
5 chester and State of New York, have invented certain new and useful Improve-
ments in Variable-Speed Conveyers, of which the following is a specification.

This invention relates to conveying appa-
10 ratus and is particularly designed for use as a delivery mechanism for book covering machines.

In the prior art of bookbinding, book covering machines in which an endless con-
15 veyer is employed to carry the books consecutively in a vertical position from one operating means to another in order to have performed thereon the successive steps nec-
essary in applying a cover to a book, are
20 well known. The book carrying conveyers in such machines are ordinarily driven at a constant speed and, when the operations employed in applying the covers are completed, the books are carried to a point in
25 the path of travel of the conveyer where they are discharged in comparatively rapid succession and at substantially regular intervals. A delivery mechanism that has been employed for conveying books away
30 from the point of discharge to the place where they are packed or stacked consists of an endless carrier provided with blades or leaves spaced apart a distance substantially equal to the thickness of the books being
35 operated upon. It will be seen that the books are thereby held by the delivery mechanism in the same vertical position in which they are received from the machine. It will also be seen that if the delivery
40 mechanism were arranged to receive and deliver comparatively thin books, it would not be sufficient merely to increase the space between the book supporting blades. If this alone were done without increasing the
45 speed of the delivery mechanism, the books would not be removed from the machine with sufficient rapidity to make way for succeeding thick books which, because of the constant speed of operation of the machine
50 conveyer, would be discharged from the machine at the same rate at which thin books would be discharged. On the other hand, if the delivery mechanism were arranged to operate with comparatively thick books, it
55 would not operate properly with thin books

as the book supporting blades would be spaced too far apart to properly support the books; or, if spaced sufficiently close together, the book receiving spaces would not all be supplied because of the high speed 60 of travel of the delivery conveyer.

The main object of this invention is to provide a delivery mechanism the speed of operation of which may be varied to meet 65 the requirements in handling books of various thicknesses.

The invention consists principally in a delivery conveyer in which the distances between the upright spacing members thereon for the reception and support of books 70 in an upright position are variable to accommodate books of different thicknesses, the number of the spacing members also being variable; and in means for so varying the speed of operation of the delivery con- 75 veyer that an upright spacing member will be presented, at the delivery point of a book conveyer, at intervals corresponding to the intervals at which books are released by said book conveyer. 80

Other features of the invention will be referred to as the description proceeds.

In the drawings, in which a preferred embodiment of the invention is illustrated, like reference characters are used to designate like parts. 85

Figure 1 is a side elevation of a device embodying the invention and showing its relation to a book covering machine.

Fig. 2 is a transverse vertical section 90 taken through the conveyer along the line 2-2 of Fig. 1.

Fig. 3 is a horizontal section of a part of the delivery mechanism taken along the line 3-3 of Fig. 1 and showing the change 95 speed gearing.

Fig. 4 is a side view of the bearing end of the delivery conveyer showing the change speed gearing.

In the particular embodiment of the in- 100 vention chosen for illustration there is shown a book conveyer arranged to serve as a delivery mechanism for a book covering machine of the type in which a horizontally traveling conveyer carries, from one operating mechanism to another, the books, successively, in a vertical position with their backs lowermost, and finally deposits the covered book at the delivery apparatus. The usual method for carrying 110

the books by the covering machine conveyer is to provide clamps which are ordinarily opened, by the action of stationary cams carried by the frame-work of the machine, 5 to discharge the books. The delivery mechanism employed is of the endless carrier type and operates to convey the books away from the machine in a direction transverse to the path of travel of the covering machine conveyer.

In this instance, the delivery mechanism is of the endless carrier type just referred to and is arranged with its receiving end located beneath the main conveyer of the 15 book covering machine as is shown in Fig. 1, of the drawing. The endless conveyer 1 constituting the delivery apparatus, is carried by the sprockets 2 and 3 which are in turn mounted on the framework 4. The 20 conveyer is made up of blades 5 which project outwardly from links 6 and serve to support the books as they are fed from the book covering machine in a vertical position until they are carried to the point 25 where they are finally delivered. The book covering machine 7 is provided with a conveyer shown in cross section at 8 which in turn is provided with book carrying clamps 9 having movable jaws 10 adapted to be 30 controlled by cams 11 fixed to the framework of the machine. The cam 11 bears such relation to the delivery mechanism that each book clamp as it arrives over the receiving end of conveyer 1 is opened and the 35 book carried thereby dropped into place on the conveyer.

For the purpose of properly receiving the books, an inclined plate 12 forming a guiding member is so arranged that the book is 40 received thereon and directed into a position resting on one of the links of the conveyer. This plate or guide member 12 is provided at its central portion with an opening 13 through which the blades 5 of the 45 conveyer pass as they move upwardly to book engaging position. It will be seen that the blades as they pass through the guide plate 12 will engage the book resting against the guide plate and carry it forwardly as the conveying blades continue 50 their movement to the outer end of the conveyer.

In order to properly align the books as they are carried by the conveyer, a jogging member 14 is mounted on an arm 15 pivoted to rock about a point 16 on the framework of the conveyer. The member 14 is adapted to engage an end of the books as they are being carried by the conveyer and jog them 55 into alignment. In order to rock the jogging member 14 about a pivot 16, a drive shaft 17 is provided with a crank 19 directly connected to the arm 15 through a link 20. The shaft 17 may be driven in any suitable manner from a shaft 36, as by means of an

intermeshing gear, not shown, carried by the shaft. On the shaft 36 is mounted a bevel gear 18 meshing with a corresponding gear 37 on a stub shaft 38. A gear 39 fixed to a shaft 38 meshes with a gear 40 on the 70 main drive shaft 41 of the book covering machine and power is thus conveyed from the drive shaft 41 through gears 40 and 39 and bevel gears 37 and 18 to shaft 36 from whence it is, in turn, delivered to shaft 17 75 and through crank 19 and link 20 to arm 15. The jogging member is thereby intermittently operated to jog the books into alignment. The jogging member 14 may be adjusted in the end of arm 15 by means of a 80 screw 21 in order to adapt the plate to register books of different size.

The conveyer 1 is driven continuously from sprocket 22 mounted on drive shaft 41 of the book covering machine. A sprocket 85 chain 23 serves to convey motion from sprocket 22 to a sprocket 24 mounted on a stub shaft 25 carried by the framework of the conveyer. The shaft 25 carries a pinion 26 meshing with a pinion 27 carried by the 90 main driving shaft 28 of the conveyer mechanism. A second shaft 29 carried in the conveyer framework 4 carries the sprockets 2 which serve to directly drive conveyer 1. A gear 30 loosely mounted on shaft 29, but 95 adapted to be locked thereto, meshes with pinion 27 and forms a driving connection which may be made use of to convey power from driving shaft 28 to the driven shaft 29.

A second gear 31 rigidly carried by driving shaft 28 meshes with a gear 32 also loosely mounted on shaft 29 and having means to lock the pinion to the shaft to form a second driving connection between driving shaft 28 and the driven shaft 29. The 105 two sets of gears 27 and 30 and 31 and 32 are given different gear ratios so that shaft 29 may be driven from driving pinion 26 at a gear ratio of, for instance, 1 to 4 in one case and of 1 to 8 in the other. These gear ratios 110 may, of course, be altered in accordance with the different requirements of different grades of work.

In order to lock one or the other of gears 30 or 32 to shaft 29 locking screw holes 115 33 and 34 are provided. A flange 35 is permanently keyed to shaft 29 and forms a bearing 43 for gear 32. The locking screw hole 33, already referred to, is adapted to extend through the hub member 36 and into gear 30 into which a screw 42 may be inserted to lock the hub, and consequently shaft 29, to gear 30. It will be seen that with this arrangement, shaft 29 is driven through its connection with gear 30 and pinion 27 at the 125 preferred gear ratio of, say, 1 to 4. Should it be desired to drive shaft 29 at the other possible speed, locking screw 42 is removed and a locking screw inserted in the screw hole 34 in flange 35 and gear 32 to thereby 130

lock gear 32 to flange 35 and shaft 29. It will be seen that when this arrangement is made, shaft 29 will be driven through gear 32 and pinion 31 on the drive shaft 28. 5 When either of gears 30 or 32 is locked to shaft 29, it will be apparent that the remaining gear is free to rotate thereon.

It is believed that the operation of the device will be clear from the above description. 10 It will be seen, that when thick books are being fed from book clamps 10 at the same rate that thin books are fed, it becomes necessary to drive the conveyer at a faster speed in order to move the thicker books out 15 of the way as the following ones are dropped into place in the conveyer. To make the speed of the conveyer conform to books of different size, it is preferred to provide interchangeable conveyer chains 20 having blades spaced at different distances apart. For instance, a conveyer having blades provided on every link may be used for thin books and a conveyer having blades mounted only on alternate links for delivering books of larger size. The blades, 25 obviously, may be of different lengths to correspond with the different sizes of the books, if found to be desirable.

It will be seen that a book delivering conveyer has been provided, the speed of which can be changed to accord with books of different size delivered to it by a book covering machine operating at a constant speed.

The feature of having a longitudinal book conveyer with a downwardly opening clamp to support a book in upright position together with means for causing the clamp to

release the book into an inclined chute below the clamp and an endless delivery conveyer adjacent to the chute and moving transversely of the longitudinal conveyer provided with upstanding leaves that pass through an opening in the chute and assume an inclined position during the passage of the book from one conveyer to the other and to 45 maintain it in an upright position is not claimed in this application but forms the subject-matter of and is claimed in a companion application Ser. No. 855,646, filed 50

August 7, 1914.

What is claimed is:

A book covering machine delivery mechanism comprising: a horizontally extending book conveyer carrying books in an upright position, means causing said book conveyer 55 to release books, regardless of thickness, at regular intervals at a delivery point, a delivery conveyer, below the book conveyer, extending horizontally away from said delivery point, means affording a variable 60 number of variably spaced upstanding spacing members on said delivery conveyer for the reception of books, from the book conveyer, of variable thicknesses and in an upright position, and means for varying the 65 speed of the delivery conveyer to present an upright spacing member at the delivery point at intervals corresponding to the release of books by the book conveyer.

Signed at New York city, in the county 70 of New York and State of New York, this 17th day of October, A. D. 1916.

CHARLES A. JUENGST.
